REINFORCING SPACER FOR INSTALLING LATCHSETS IN HOLLOW DOORS

Ernest L. Schlage, Burlingame, and John Henry Brauen, Brisbane, Calif., assignors to Schlage Lock Company, a corporation

Filed May 8, 1958, Ser. No. 734,001

9 Claims. (Cl. 70—451)

This invention relates to latchsets and particularly to tubular latchsets employed with hollow doors.

In the conventional tubular latchset or lockset installation the latch actuating mechanism is mounted on the door by means of a pair of clamping plates which are usually pulled together by clamping screws. In tightening the clamping screws an appreciable compressive load is applied to the door which, if solid, is usually sufficiently strong to resist such load. However, in the case of metal doors, that are usually hollow, the clamping load deflects the opposed door panels inwardly to an objectionable degree. Although a reinforcing frame or spacer may be secured between the door panels during fabrication of the door, the proper location of such spacer may not be determined until after the door is installed since such location depends upon the lockset employed. Furthermore, in many instances, it is desirable to be able to install a new latchset or lock in a different location after the door has been in use.

The main object of the present invention is therefore the provision of a reinforcing frame or spacer between the opposite panels of a hollow door that may be installed after the door has been fabricated.

Another object of the invention is the provision of a spacer for reinforcing a hollow door adjacent the latch-bolt and which spacer serves as a support for the latch-bolt housing.

Still another object is the provision of an extremely simple and inexpensive means for reinforcing a hollow door and which means may be quickly applied by the person installing the latchset.

Other objects and advantages will be apparent from the drawings and from the specification.

Fig. 1 is an exploded perspective of a fragmentary portion of a door showing the invention in use between the door panels and also showing the clamping means for securing the latch actuating mechanism in place together with the latch bolt unit.

Fig. 2 is an enlarged perspective of one of the two elements comprising the spacer of the present invention.

Fig. 3 is a side elevation of the assembled spacer.

Fig. 4 is an end elevation of the spacer.

Fig. 5 is a view similar to Fig. 3 but showing the spacer expanded.

Fig. 6 is an end elevation of the spacer of Fig. 5.

Fig. 7 is a side elevation of the spacer of Fig. 5 showing another method of assembly.

Fig. 8 is an end elevation of the spacer of Fig. 7.

Fig. 9 is a vertical cross section through a hollow door showing the invention in place in a completed latchset installation.

In detail, and with reference to Figs. 1 and 9, the invention is adapted to be employed in a hollow door having a pair of spaced apart door panels 1, 2, and an edge 3 joining said panels.

A hole 4 is drilled in the edge 3 for receiving therethrough the latch bolt unit generally designated 5. Circular openings 6, 7 are provided in panels 1, 2, for re-

2

ceiving therethrough the latch bolt actuating mechanism of whatever design is employed. In Figs. 1, 9, a simple form of mechanism is shown which includes a pair of inner and outer clamping plates 11, 12 respectively.

5 Each plate is provided with a hub 13 which serves as a bearing for the associated spindle. Spindle 14 is shown in Fig. 9 carrying a knob 15 by which the spindle is rotated.

Carried by clamping plate 12 are a pair of U-shaped posts 16, 17 provided with screws 18 which cooperate with holes 19 in clamping plate 11 for tightening the plates 11, 12 against the oppositely outwardly directed sides of panels 1, 2. Details of this clamping mechanism are disclosed in U.S. Patent No. 2,804,334. The particular structure employed forms no part of the instant invention and may take any form so long as clamping means is provided.

The invention comprises a pair of identical elements A, B respectively, one of which is shown in detail in Fig. 2. Each element may be of sheet metal and is substantially U-shaped and comprises a pair of opposed parallel sides 23, 24 connected together by an end portion 25 at right angles to sides 23, 24.

25 Side 23 is formed with an outwardly opening recess 26 which is semicircular at its inner end as indicated at 27. Recess 26 thus forms a pair of parallel legs 28, 29 on side 23 extending at right angles to connecting portion 25. Leg 28 is formed to provide an elongated slot 32 and leg 29 is provided with a pair of projections 33, 34, struck outwardly from the sheet metal of side 23.

30 Side 24 is similarly formed with an outwardly opening recess 35 including a semicircular portion 36 and also includes a pair of legs 38, 39 identical to legs 28, 29 respectively. Leg 38 is provided with an elongated slot 42 and leg 39 carries a pair of projections 43, 44. Although sides 23, 24 are similar in construction, it will be noted that legs 28, 38 which are provided with slots are diagonally arranged as are legs 29, 39 which are provided with projections. By this arrangement element

35 B may be assembled with element A so that the sides 23, 24 of element B are slidably received between the corresponding sides 23, 24 of element A as shown in Figs. 3, 4. Because of the similar construction of the elements the projections 33, 34 of side 23 of element B may be snapped within slot 32 of side 23 of element A. Similarly, projections 43, 44 of side 24 of element B may be snapped within slot 42 on side 24 of element A.

40 Sliding movement of element B away from element A is limited by engagement of projections 33, 43 of element B with the outer ends of slots 32, 42 that are remote from end portion 25 on element A.

45 Since the two elements A, B are identical it obviously makes no difference which element is received within the other to accomplish the desired result.

In Fig. 4 there is indicated schematically by means of 50 dot-dash circle 47 the extent of holes 6, 7 in panels 1, 2, respectively. When the spacer A, B is in the collapsed form of Figs. 3, 4, it will be noted that its lateral extent is so reduced that it may be passed through said holes. However, when it is expanded to the position of Figs. 5, 6 it is of sufficient lateral extent to extend beyond the side-walls of holes 6, 7. Thus when the spacer A, B is received between panels 1, 2 and expanded as shown in Fig. 9 with the sides 23, 24 and end portions 25 at right angles to door panels 1, 2, said spacer spaces apart said panels and resists the compressive load applied to said panels during the installation of the latchset. It will be understood of course that the length of end portions 25 and sides 23, 24 is equal to the spacing between panels 1, 2.

70 To permit positioning the spacer A, B with its central axis coaxial with holes 6, 7 in panels 1, 2, sides 23,

24 are provided with coplanar extensions 48 which form outwardly directed shoulders 49. The position of shoulders 49 is predetermined so that when the device is almost completely expanded to the form shown in Figs. 5, 6 said shoulders abut the radially inwardly directed surface of the adjacent hole 6 or 7. Because of the symmetry of elements A, B, the spacer is thus positioned coaxial with the holes 6, 7.

The method of installing the spacer is as follows: the spacer is collapsed to the position of Fig. 4 and inserted through either hole 6 or 7 in the door panels 1, 2. The user may then reach into the spacer from opposite sides of the door and expand the device by means of two fingers to the position of Figs. 6, 9. Very little care is required to insure that all eight shoulders 49 abut the radially inwardly directed surfaces of holes 6, 7. The spacer is thus securely held in place against movement in any direction except that the spacer may be rotated about its axis with the shoulders 49 sliding on the radially inwardly directed surface of holes 6, 7.

To remove the spacer it is merely necessary to rotate the same to a position with the sides 23, 24 horizontal and with the end portion 25 of one element adjacent latch bolt opening 4 in edge 3. The user may then reach through hole 4 and push on such adjacent end portion to collapse the spacer. In this connection it will be noted that the shoulders 49 engaging the sides of holes 6, 7 that are remote from edge 3 will resist movement of the adjacent element thus permitting the other element to be slidably moved to collapse the spacer. When the spacer is thus collapsed it may be removed through either of the holes 6, 7.

It will be seen from Fig. 5 that the semicircular portions 27 on sides 23 of elements A, B cooperate to form a circular opening 27 and similarly the semicircular portions 36 on sides 24 cooperate to form a similar opening 36. As best seen in Figs. 1, 9, said openings 27, 36 are arranged in planes parallel to the edge 3 of the door when the spacer is installed as above described. Said openings are predetermined in size so that the housing of the latch unit 5 is snugly received within the same when said latch unit is inserted through opening 4 in edge 3. It will be apparent that said latch unit is thus provided with three points of support and if the axes of openings 6, 7 and opening 4 are coplanar, as they should be, the openings 27, 36 automatically position the latch unit 5 on the desired horizontal axis. Accurate assembly of the latch bolt unit and the actuating mechanism is thus insured and no particular degree of care is required on the part of the operator.

The elements A, B may be assembled in other ways than that shown in Figs. 3, 4. For example, instead of placing both sides 23, 24 of one element between the sides of the other element so that two sets of projections do not function, an arrangement such as shown in Figs. 7, 8 may be employed. In this case, leg 29 of element B is again placed inside leg 28 of element A but leg 28 of element B is placed outside leg 29 of element A. Similarly side 24 of element B is arranged with its legs 38, 39 inside and outside respectively of the corresponding legs of element B. By this arrangement the projections 33, 34, 43, 44 are all received within slots formed in an adjacent side. However, the assembly shown in Figs. 3, 4 is adequately strong and is the easiest to assemble.

It is apparent that the invention not only provides a frame or spacer for stiffening the door, but also facilitates accurate mounting of the latchset and prevents loads on the knob from being transferred to the latchbolt housing.

The very specific description of the preferred embodiment of the invention is not to be taken as restrictive of the invention as it is obvious that various modifications in design will occur to those skilled in the art without departing from the spirit and scope of the invention or from the attached claims.

We claim:

1. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter.

2. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter, said elements cooperating when expanded to form an opening in a plane at right angles to said panels for snugly receiving a latch unit therethrough.

3. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter, said elements being formed with shoulders adapted to engage the radially inwardly directed surface of one of said openings when said spacer is expanded for positioning said spacer in a vertical direction.

4. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings, to permit passing said spacer through one of said openings, and expandable to a lateral extent greater than the extent of said openings to permit said spacer to be expanded into spacing relationship with said panels when it is between the latter, said elements cooperating when expanded to form an opening in a plane at right angles to said panels for snugly receiving a latch unit therethrough, said elements being formed with shoulders adapted to engage the radially inwardly directed surface of one of said openings when said spacer is expanded for positioning said spacer in a vertical direction, said shoulders being equally spaced vertically from said latch unit receiving opening when in engagement with said

surface whereby said latch unit is supported with its axis intersecting the axis of said panel openings.

5. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter, each of said elements being substantially U-shaped with the opposed sides of one of said elements slidably engaging the opposed sides of the other element to form a generally rectangular hollow spacer.

6. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter, each of said elements being substantially U-shaped with the opposed sides of one of said elements slidably engaging the opposed sides of the other element to form a generally rectangular hollow spacer, and stop means on said sides for limiting sliding movement of said elements toward and away from each other.

7. A reinforcing member for a hollow door having a pair of spaced apart panels each provided with an opening, said openings being coaxial and adapted to receive a latch actuating mechanism therethrough, said member comprising: a pair of interengaging elements assembled to provide a hollow spacer extending between and in engagement at its opposite ends with the opposed inner surfaces of said panels, said elements being supported for movement toward each other to collapse said spacer laterally to a lateral extent less than the extent of said openings to permit passing said spacer through one of said openings, and expandable to a lateral extent greater than the extent of said openings to permit said spacer to be expanded into spacing relationship with said panels when it is between the latter, each of said elements being substantially U-shaped with the opposed sides of one of said elements slidably engaging the opposed sides of the other element to form a generally rectangular hollow

5 spacer, one pair of the engaging sides of said elements being each formed with an outwardly opening recess cooperating to form an opening in said spacer in a plane at right angles to said panels for snugly receiving a latch unit therethrough.

10 8. A reinforcing member for a hollow door having a pair of spaced panels provided with coaxial openings adjacent the edge of said door for receiving a latch actuating mechanism therethrough, and provided with an opening in said edge for receiving a latch unit therethrough with the axes of said mechanism and said unit in intersecting relationship, said member comprising: a pair of similar substantially U-shaped elements each provided with a pair of opposed sides and an end portion connecting said sides, said elements being slidably mounted relative to each other with the sides of one element in sliding engagement with the corresponding sides of the other element to form a generally rectangular hollow spacer engageable at its opposite ends with the opposed inner surfaces of said panels, said elements being slideable toward each other to collapse said spacer to permit passage of the same through one of said panel openings and slideable away from each other to expand said spacer to a cross sectional extent greater than the extent of said panel openings to permit said spacer to be positioned coaxial with said openings and in spacing relationship with said panels.

15 9. A reinforcing member for a hollow door having a pair of spaced panels provided with coaxial openings adjacent the edge of said door for receiving a latch actuating mechanism therethrough, and provided with an opening in said edge for receiving a latch unit therethrough with the axes of said mechanism and said unit in intersecting relationship, said member comprising: a pair of similar substantially U-shaped elements each provided with a pair of opposed sides and an end portion connecting said sides, said elements being slidably mounted relative to each other with the sides of one element in sliding engagement with the corresponding sides of the other element to form a generally rectangular hollow spacer engageable at its opposite ends with the opposed inner surfaces of said panels, said elements being slideable toward each other to collapse said spacer to permit passage of the same through one of said panel openings and slideable away from each other to expand said spacer to a cross sectional extent greater than the extent of said panel openings to permit said spacer to be positioned coaxial with said openings and in spacing relationship with said panels, said sides being provided with shoulders adapted to engage the radially inwardly directed surface of one of said panel openings for limiting the expansion of said spacer and for positioning the latter vertically.
